UNITED STATES PATENT OFFICE

HARRY R. GRACE, OF PHILADELPHIA, PENNSYLVANIA, ASSIGNOR TO
THOMAS B. HAGSTOZ AND CHARLES N. THORPE, OF SAME PLACE.

ADVERTISING-CARD.

SPECIFICATION forming part of Letters Patent No. 279,866, dated June 19, 1883.

Application filed December 27, 1882. (No model.)

To all whom it may concern:

Be it known that I, HARRY R. GRACE, of the city of Philadelphia, county of Philadelphia, and State of Pennsylvania, have invented an Improvement in Advertising-Cards, 5 of which the following is a specification.

My invention has reference to advertising cards or circulars; and it consists of a paper or card shaped like a watch-case, and formed 10 of two or more disks or leaves connected together or stamped from one sheet of paper or card-board; further in printing on or otherwise forming the two outer faces of said leaves or disks, so that when the same are folded in 15 they represent the lids of a watch-case, and providing any one of said leaves with the representation of a pendant and ring made integral therewith or secured thereto, all of which is more fully set forth in the following 20 specification, and shown in the accompanying drawings, which form part thereof.

It is common to stamp paper or card-board, so that the leaves shall be hinged together and 25 bent back and forth upon themselves, with views of cities or scenery printed thereon, the device as a whole being known as "panoramic views." I am also aware that it is not new to place such panoramic views in covers or cases, or various shapes designed to protect them, as that is substantially shown in 30 English Patent No. 2,563 of 1869; therefore it is not designed that this invention shall cover such devices.

The object of my invention is to form an attractive advertising card or circular for the 35 watch or watch-case trade. The outside of the circular represents a watch, while the inside leaves or faces may be used to contain the advertisement, and, if desired, one or more 40 of the faces may be made for memorandum purposes, either with plain paper or with a surface capable of allowing the pencil-marks being erased.

In the drawings, Figure 1 is a side elevation 45 of the card open. Fig. 2 is a similar view from the other side. Figs. 3 and 4 show modified forms of my invention.

A is the disk, which corresponds to the center-piece of the watch-case, and is provided 50 at the top with the pendant and ring E.

B and C represent the lids, and are printed or stamped upon one side to correspond to the engraving on the case, and may be printed in gold, silver, or colors. Both of said disks B and C are secured to the part A by hinge-pieces D, which, when the disks or lids B and C are bent up against part A, (one being on each side,) correspond to the usual hinges on watch-cases. Both faces of part A and one face of parts B and C are left plain, or may be 60 printed upon as an advertisement.

If desired, one of the cases may be represented on one side of the piece A, and one of the parts B or C may be plain on both sides; but I prefer the construction above described. 65

If desired, four or more disks may be used and arranged about the part A as shown in Fig. 3; and, in lieu of hinging them all to one piece, they may be hinged together alternately at top d and bottom D, as shown in Fig. 4, in 70 which one of the watch-case faces is on A and the other on B, the plain parts or disks being shown at C.

In place of the lid being represented on the outside of the disks, an open-faced watch may 75 be shown, and, if desired, the works may be shown on the other outer face or on the part A.

I do not limit myself to any particular manner of printing or forming the cards to represent a watch, as it may be varied in numerous 80 ways without departing from my invention.

The design broadly for an advertising-card formed of a single piece of card-board or paper, and shaped to represent a watch, will form 85 subject-matter of another application.

Having now described my invention, what I claim as new, and desire to secure by Letters Patent, is—

1. An advertising card or circular formed of two or more disks stamped from suitable 90 material and integral with each other, and which when folded represent a watch-case, substantially as and for the purpose specified.

2. An advertising card or circular formed of two or more disks made integral with each 95 other, and which when folded represent a watch-case, the two outer faces of said disks being printed to represent the lids of a watch-case, substantially as and for the purpose specified. 100

3. An advertising card or circular which consists of three or more disks stamped out of paper or card-board and hinged together, one of said disks being blank and provided with the representation of a pendant and ring, and the others of said disks being arranged at angles to each other, having their opposite sides printed to represent the lids of a watch, and so arranged that when bent down upon the

first-named disk they completely inclose it, substantially as set forth.

In testimony of which invention I hereunto set my hand.

HARRY R. GRACE.
